US0D1112234S

(12) **United States Design Patent** (10) Patent No.: **US D1,112,234 S**
(45) Date of Patent: ** Feb. 10, 2026

(54) **EXTENDER FOR A MEMORY DEVICE MOUNTING ADAPTOR**

(71) Applicant: **Intel Corporation**, Santa Clara, CA (US)

(72) Inventors: **Marc Milobinski**, Scappoose, OR (US); **Cong Zhou**, Shanghai (CN); **Ting Li**, Shanghai (CN); **Grant Steen**, Bellevue, WA (US)

(73) Assignee: **Intel Corporation**, Santa Clara, CA (US)

(**) Term: **15 Years**

(21) Appl. No.: **29/881,163**

(22) Filed: **Dec. 28, 2022**

CLAIM

The ornamental design for an “extender for a memory device mounting adaptor” as shown and described.

DESCRIPTION

FIG. 1 is a right, front perspective view of an extender for a memory device mounting adaptor.

FIG. 2 is a right, rear perspective view of the extender of FIG. 1.

FIG. 3 is a top view of the extender of FIG. 1.

FIG. 4 is a bottom view of the extender of FIG. 1.

FIG. 5 is a right side view of the extender of FIG. 1; and, FIG. 6 is a left side view of the extender of FIG. 1.

The even broken lines indicate environmental structure of the claimed design and form no part thereof. The dash-and-dot broken lines indicate boundaries of the claimed design and form no part thereof.

1 Claim, 6 Drawing Sheets
